UNITED STATES PATENT OFFICE.

OLIVER D. CORNELL, OF HARTFORD, CONNECTICUT.

GAS-BURNER.

SPECIFICATION forming part of Letters Patent No. 757,651, dated April 19, 1904.

Application filed July 15, 1903. Serial No. 165,586. (No model.)

To all whom it may concern:

Be it known that I, OLIVER D. CORNELL, a citizen of the United States, and a resident of Hartford, in the county of Hartford and State 5 of Connecticut, have invented certain new and useful Improvements in Gas-Burners, of which the following is a specification.

The invention relates to gas-burners or means for controlling the fluid, and more particularly to a device arranged to have certain automatic action dependent upon the flow of the fluid through the apparatus and directly dependent upon the temperature induced by said fluid.

15 The object of the invention is to provide a simple and compact device which may be readily applied to an ordinary illuminating-gas burner and which will whenever the supply of gas is cut off momentarily or the flame otherwise extinguished react to cut off the flow of gas or other fluid.

20 A further object of the invention is to provide an automatic cut-off for burners which will act under varying conditions of temperature induced by the gas ignited at the burner.

25 A still further object is to provide an arrangement which applied to an ordinary gas burner or tip will not deflect or interfere with the light or cast unpleasant shadows; and a 30 still further object is to provide in such a device a means for opening and holding open a supply-valve, at the same time throwing the parts automatically into position to be released upon a predetermined decrease in temperature due to the reduction of the flame.

35 Referring to the drawings, Figure 1 is a view in side elevation of the improved burner. Fig. 2 is a plan view of the parts shown in Fig. 1. Fig. 3 is an end view looking from 40 the right of Fig. 1. Fig. 4 is a detail view of the trip mechanism. Fig. 5 is a detail view of the end of the valve-lever. Fig. 6 is a detail view of the controlling-lever.

In the accompanying drawings the letter *a* 45 denotes a burner-tube of ordinary construction having at or near its base a valve *b*, which may be of any desired pattern and is held normally in closed position by a reactive spring *b'*. Mounted upon the spindle of this 50 valve is a lever *c*, having a projecting arm *c'*,

to which is connected a chain *d*. A pin *d'* and segmental slot *d''* determine the movement of the lever and valve-stem.

Suitably mounted upon the burner-tube and secured thereto, as by a screw or other suitable clamp, is a base-piece *e*, having secured at one end a support *e'* for a thermostatic bar *f*. This bar *f* is of peculiar shape, having a main body portion *f'* and a projecting ear *f''*, thus making a most sensitive bar and one which will vary with slight degrees in changes of temperature. This thermostatic bar has at the opposite end from its support a dependent connection *g*, which lies in the forked end of a lever *h*, pivoted to the frame, as at *h'*, 65 and lying in a depressed portion of the base *h''*. The end *i* of this lever is beveled on its inner face and normally projects against the surface of a spring-pressed pin *k*. The lever *c* at its upper end is of blade shape and normally lies between the lever *h* and the base-piece. When the gas is turned on, the chain, heretofore described, is pulled downward, drawing the lever *c* back until the blade-shaped edge rests against the surface of the spring- 70 pressed pin. In this position the valve is positively held open, and when the gas is ignited the heat expands the thermostatic bar and presses the end of the lever *h* inward against the pin, moving it forward out of engagement with the blade-shaped edge of the valve-lever. The valve-lever now comes into contact with the extreme end of the lever *h* and rests there until the contraction of the thermostatic bar reacts upon the lever and 75 permits the valve-lever *c* to be thrown forward to the cut-off position by its spring.

It is to be noted that the projecting portion of the thermostatic bar is bent forward slightly over the jet of the frame in order to 80 take up heat when the supply is turned down to a very low point. While numerous devices employing thermostatic bars and rings have been in common use for automatically cutting off the supply of gas from a burner when the 85 flame is extinguished, in all of these devices the flame must be run at practically full force in order to keep the parts in position with the valve open. In the device herein described the thermostatic bar is so arranged and 90

formed that comparatively little heat from the burner-tube will be properly transmitted to hold the valve open, and yet the device is most sensitive to changes of temperature, and 5 the delicacy, while entirely practical, with which the valve-lever is held in open position permits and compels closing of the valve within an extremely short space of time after the flame, be it ever so small, is extinguished.

10 Obviously the thermostatic bar might be arranged in various different manners, and, in fact, the several parts of the mechanism might be varied as to details and arrangement without materially departing from the spirit or 15 intent of the invention, and obviously any desired material might be used for a thermostatic bar—as, for instance, aluminium, German silver, or two metals combined—although it is desirable to use metals having a high coefficient of expansion and contraction. By having the thermostatic bar formed with a projecting portion practically overlying the jet from the burner the bar simply takes up its heat and just as simply radiates it, aided by 20 the flow of fluid after the flame is extinguished 25 and until the bar has reacted to close the valve.

What I claim as my invention, and desire to secure by Letters Patent, is—

1. In combination with a burner, a valve, 30 a spring for closing the valve, a valve-lever for controlling the movements of the valve, a reciprocating pin forming a positive stop for the valve-lever in one position, a thermostatic bar operatively arranged with relation 35 to the burner, and means intermediate said thermostatic bar and pin for moving the latter and permitting the engagement of the lever and the pin-moving means.

2. In combination with a burner, a thermostatic bar operatively arranged with relation 40 to the burner, a valve and a valve-lever for controlling the movements of the valve, a spring for normally holding the valve in a closed position, a trip-lever connected at one 45 end to the thermostatic bar and actuated thereby and having its opposite end arranged adjacent to a stop-pin, a stop-pin for positively holding the valve-lever in open position and arranged to release the valve-lever and throw 50 it into direct contact with its coöperating lever upon predetermined movements of the thermostatic bar.

3. In combination with a burner, a valve for controlling the flow of fluid to the burner, a 55 lever for actuating said valve, the latter normally held in closed position by a spring, the lever-spring, a positive stop for locking the valve-lever with the valve in open position and automatic means including a thermostatic 60 bar for releasing the lever from the positive stop and afterward controlling its movements dependent upon the temperature of the thermostatic bar.

4. In combination with a burner, a valve for 65 controlling the flow of fluid to the burner, a

thermostatic bar for controlling the closing movements of the valve, said bar arranged adjacent to the flame of the burner and having centrally arranged thereon a projecting part for conducting heat to the bar and radiating 70 heat therefrom.

5. In combination with a burner, a valve for controlling the flow of fluid to the burner, a valve-lever for actuating the valve, a base-piece secured to the tube and having a depressed portion at one end, a lever pivoted in said depressed portion and bearing at one side against a resilient projection on the base-piece and having its end adapted for free engagement with the valve-lever. 80

6. In combination with a burner, a valve controlling the flow of fluid through the burner, a lever for actuating said valve, a resilient stop for positively locking the valve-lever and valve in open position, and automatic means including an expanding thermostatic member for moving said resilient stop and releasing the valve member for engagement therewith whereby said lever will assume a position adjacent to the stop-actuating 90 means and will be released from said position by the contractile movement of the thermostatic member. 85

7. In combination with a burner, having a valve for controlling the flow of fluid to the 95 burner, a valve-lever for actuating said valve, a spring for normally holding the valve in closed position, a thermostatic bar, a spring-actuated pin arranged to form a positive stop to hold the valve-lever with the valve in open 100 position said valve-lever resting against the periphery of the pin, a trip-lever connected at one end to the thermostatic bar and actuated thereby and having its end arranged to contact with the end of the stop-pin whereby 105 an expansive movement of the thermostatic bar depresses the pin and releases the valve-lever to a position at the end of the pin and adjacent to the contacting portion of the trip-lever and upon a contractile movement of said 110 bar will release said lever for a closing movement.

8. In combination with a burner having a valve for controlling the flow of fluid through the burner, a valve-lever for actuating said 115 valve provided with a blade-like end, a spring-pressed stop, actuating means for said stop including a thermostatic bar and a lever the latter provided with a cam-surface adjacent to the stop whereby the valve-lever may be 120 freely moved between the stop and its engaging lever in one direction and will engage the resilient stop and be released therefrom for engagement with its actuating means dependent upon the action of the thermostatic bar. 125
